CLAIM

The ornamental design for the chair, as shown and described.

DESCRIPTION

FIG. 1 is a front perspective view of the chair design of the present invention;

FIG. 2 is a rear perspective view of the chair design shown in FIG. 1;

FIG. 3 is a left side elevational view of the chair design shown in FIG. 1;

FIG. 4 is a front elevational view of the chair design shown in FIG. 1;

FIG. 5 is a rear elevational view of the chair design shown in FIG. 1;

FIG. 6 is a top plan view of the chair design shown in FIG. 1;

FIG. 7 is a bottom plan view of the chair design shown in FIG. 1;

FIG. 8 is a front perspective view of a second embodiment of the chair design of the present invention;

FIG. 9 is a front elevational view of the chair design shown in FIG. 8;

FIG. 10 is a top plan view of the chair design shown in FIG. 8;

FIG. 11 is a front perspective view of a third embodiment of the chair design of the present invention;

FIG. 12 is a rear perspective view of the chair design shown in FIG. 11;

FIG. 13 is a left side elevational view of the chair design shown in FIG. 11;

FIG. 14 is a front elevational view of the chair design shown in FIG. 11;

FIG. 15 is a rear elevational view of the chair design shown in FIG. 11;

FIG. 16 is a top plan view of the chair design shown in FIG. 11;

FIG. 17 is a bottom plan view of the chair design shown in FIG. 11;

FIG. 18 is a front perspective view of a fourth embodiment of the chair design of the present invention;

FIG. 19 is a rear perspective view of the chair design shown in FIG. 18;

FIG. 20 is a left side elevational view of the chair design shown in FIG. 18;

FIG. 21 is a front elevational view of the chair design shown in FIG. 18;

FIG. 22 is a rear elevational view of the chair design shown in FIG. 18;

FIG. 23 is a top plan view of the chair design shown in FIG. 18; and,

FIG. 24 is a bottom plan view of the chair design shown in FIG. 18.
